US00D796499S

(12) **United States Design Patent** (10) **Patent No.:** **US D796,499 S**
(45) **Date of Patent:** **** Sep. 5, 2017**

(54) **ELECTRONIC DEVICE**

(71) Applicant: **Samsung Electronics Co., Ltd.**, Suwon-si (KR)

(72) Inventor: **Sang-Uk Lee**, Seoul (KR)

(73) Assignee: **Samsung Electronics Co., Ltd.**, Suwon-si (KR)

(**) Term: **15 Years**

(21) Appl. No.: **29/528,038**

(22) Filed: **May 26, 2015**

(30) **Foreign Application Priority Data**

Nov. 26, 2014 (KR) 30-2014-0057080

(57) **CLAIM**

I claim the ornamental design for an electronic device, as shown and described.

DESCRIPTION

FIG. 1 is a front perspective view of an electronic device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view of the electronic device shown in a folded position;

FIG. 9 is a front view of the electronic device shown in FIG. 8;

FIG. 10 is a rear view of the electronic device shown in FIG. 8;

FIG. 11 is a left-side view of the electronic device shown in FIG. 8;

FIG. 12 is a right-side view of the electronic device shown in FIG. 8;

FIG. 13 is a top view of the electronic device shown in FIG. 8;

FIG. 14 is a bottom view of the electronic device shown in FIG. 8;

FIG. 15 is a front perspective view of the electronic device shown in a bent position in which the electronic device is folded;

FIG. 16 is a front view of the electronic device shown in FIG. 15;

FIG. 17 is a rear view of the electronic device shown in FIG. 15;

FIG. 18 is a left-side view of the electronic device shown in FIG. 15;

FIG. 19 is a right-side view of the electronic device shown in FIG. 15;

(Continued)

FIG. 20 is a top view of the electronic device shown in FIG. 15; and,
 FIG. 21 is a bottom view of the electronic device shown in FIG. 15.
